UNITED STATES PATENT OFFICE

JOHN R. REPROGLE, OF DETROIT, MICHIGAN, ASSIGNOR, BY MESNE ASSIGNMENTS, TO
KELVINATOR CORPORATION, OF DETROIT, MICHIGAN, A CORPORATION OF
MICHIGAN

REFRIGERATOR

Original application filed February 28, 1921, Serial No. 448,331, now Patent No. 1,719,024, and in Canada
February 11, 1922. Divided and this application filed May 14, 1927. Serial No. 191,478.

This invention relates to refrigeration apparatus and to such as are particularly adapted for domestic use, in which a cooling unit is supported within the cooling compartment of a refrigerator cabinet or the like, the present application being a division of my copending application, Serial No. 448,331, filed February 28, 1921.

This invention has for an object the provision of an improved adjustable and resilient supporting means for the cooling unit within this cooling compartment.

Another object is to provide an effective means for excluding warm outside air from the cooling unit and at the same time permit access to the ends of ice trays, food receptacles, or the like for the purpose of their insertion and removal.

Another object is the provision of an improved arrangement of cooling unit parts with respect to each other, and also with respect to the above mentioned warm air excluding means.

Another object is to provide an improved arrangement of these ice trays or food receptacles with respect to the warm air excluding means, and also with respect to certain parts of the cooling unit.

Still another object is to provide an improved means for conducting the condensed moisture and melted frost away from the front of the said warm air excluding means.

Other objects more or less incidental or ancillary to the foregoing will be apparent from an examination of the following description taken in connection with the accompanying drawings in which:

Fig. 1 is a front elevation of a refrigerator assembly, with some parts shown in section and other parts broken away.

Fig. 2 is a vertical section taken at right angles to Fig. 1.

Fig. 3 is an enlarged side elevation of the refrigerating or brine tank, with the vaporizer therein, some parts being broken away and some being shown in section.

Fig. 4 is a front elevation of the device shown in Fig. 3, some parts being broken away and some being shown in section.

50 I have shown in Figs. 1 and 2 a cabinet 1.

This cabinet is divided as shown by means of a partition wall 2 into a refrigerator compartment 3 and a machine compartment 4. The exterior top, bottom, front, back and end walls of this cabinet are designated by the reference characters 5, 6, 7, 8 and 9 respectively. These walls are rigidly secured together in any convenient manner and are braced by means of suitable bars 10 as shown in Fig. 2. A lining of insulating material 11 is provided for the refrigerator compartment 3. It will be noted that the lining provided at the ends and back of this compartment is spaced from the exterior walls of the cabinet; which construction, as will be readily understood, provides a dead air heat insulating space 12 between the refrigerator compartment 3 and the exterior walls thereof.

Located within or adjacent to the compartment 3 as for example at one side and within the upper portion of this compartment, is a relatively small refrigerating or cooling chamber 14 open at its front end and closed by the door 15. (See Figs. 1 and 2.) The walls of the compartment 3 may form two sides and the top of this chamber. The remaining side 16 and the bottom 17 of this chamber also may be provided with heat insulating material, although this is not necessary. A lining 18 of any suitable material forms the interior walls of this chamber.

Two openings are provided one above the other for the circulation of air through the chamber. As shown, the side wall 16 is provided at its upper end with an opening 19 and the bottom wall 17 is provided with an opening 20 for such circulation of air. A thermostatically controlled damper mechanism 21, which constitutes the subject matter of my copending application Serial No. 452,397, filed March 14, 1921, controls the circulation of air through the opening 20 in a manner which will be readily understood.

The arrangement of the cooling chamber provides a continuous L-shaped food compartment 22, one part thereof extending vertically along the side of the cooling chamber 14 and the other laterally beneath the said chamber. This food compartment is lined with porcelain or enameled material, as is

55

60

65

70

75

80

85

90

95

100

common in such structures. This compartment 22 is closed by any convenient arrangement of doors. As shown, this is accomplished by means of the full length main door 23, and the smaller door 24 located beneath the door 15.

The machine compartment 4 in the lower portion of the cabinet 1 is adapted to contain a motor-compressor-condenser unit. It is to be noted here that in the broader aspects of my invention it is not essential that this machine compartment be located in the same cabinet with the refrigerator compartment as the same can be installed in a remote position such as the basement or a different room of the building. This machine compartment is adapted to be closed by means of a tightly fitting door 25 so that any noise of the operating mechanism within will be reduced to a minimum.

Within this machine compartment 4 I have installed, as was stated, the motor-compressor-condenser unit which forms an essential part of a refrigerating system which maintains a low temperature in the refrigerator compartment 3. This unit comprises an electric motor 26, a compressor 27 driven by the motor, and a water cooled condenser 28. The compressor is adapted to receive vaporized refrigerant through its suction inlet, compress the vapor and discharge it into the condenser where the combined pressure and cooling liquefy it. The motor-compressor-condenser unit will not be described in detail since, so far as the present invention is concerned, any apparatus can be used that is adapted to liquefy refrigerant vapor. However, it is observed that the unit shown in the drawings is described in detail in my application Serial No. 448,331, above referred to.

The suction side of compressor 27 is connected by a conduit 29 with the vapor space of a vaporizer forming part of a cooling unit 30. The discharge port of the condenser is connected by a conduit 31 to the refrigerant inlet of the said vaporizer, said conduit being adapted to conduct liquid refrigerant to the vaporizer from the condenser. Any suitable refrigerant can be employed in so far as some features of the invention are concerned, but I prefer to use sulphur dioxide (SO_2).

Referring now to Figs. 4 and 5, it will be seen that the cooling unit 30 which is supported within the cooling chamber 14, comprises a brine tank 32 which carries in its upper left hand portion an expansion chamber or header 33. This header 33 is in effect the storage tank or chamber for the refrigerant material, and has tubes 34 depending therefrom and arranged within the brine tank for the circulation of liquid refrigerant contained in the header. The tubes are bent to form loops which have both their

ends connected to the side walls of the said header. As shown, each of the tube loops is connected at one end 35 to the left side of the header near the bottom, and at the left of the center thereof, and the opposite end 36 is connected to the right side wall of the header at a point above the left hand connection, so as to promote a circulation of liquid refrigerant in the tubes, as will be readily understood. These loops are arranged in planes parallel to each other and at right angles to the header as can be seen from an examination of Figs. 3 and 4. Within the interior of the header I have provided a float actuated valve 37 for the purpose of regulating the flow of liquid refrigerant into the header from the pipe 31. The level of liquid refrigerant is maintained above the ends of the pipe loops by means of this float valve. In the upper portion of the header I have shown an opening 38 through which the vaporous refrigerant may return by means of the pipe 29 to the suction side of the compressor as was described above. The projections 39, 39 are formed on each side of the header and rest on the top surface 40 of the brine tank 32. These projections 39, 39 form the supporting means for the header and depending tube loops arranged within the brine tank. The abutting surfaces of the header and brine tank are soldered to form liquid tight joints therebetween.

The brine tank 32 is constructed of any suitable material and has a plurality of series of aligned openings 42, 42 formed in the front and rear walls thereof. These openings are adapted to be closed by means of elongated tubular sleeves 43, 43 which form part of the wall structure of the tank, the joints between the sleeves and the said tank walls being, of course, liquid tight. The sleeves are arranged within the space defined by the tube loops and constitute food chambers adapted to receive trays or any suitable receptacles 44, 44 for the chilling of edibles or the freezing of ice, as the case might be. At 45 I have shown an opening adapted to be sealed by means of a plug 46 and through which the tank may be filled with any suitable heat conducting medium having a comparatively low freezing point, preferably calcium chloride (CaCl_2) solution. It will be seen that the cooling unit consists essentially of a vaporizer, comprising header and depending tube loops, and a brine tank in the brine of which the vaporizer is partly immersed.

The cooling unit is supported within the cooling chamber 14 by means of a plurality of cradle supports 47, 47. Each of these supports is formed by bending an ordinary flat strip of suitable metal in the form of a U, and having the upper ends of the U bent inwardly to form attaching members 48, 48. The cooling unit rests on the bottom horizontal leg of this U in the manner shown, and

is secured in position by means of suitable clamping screws 49 engaging the upper surface 40 of the brine tank 32. These screws are mounted in the horizontal flange 50 of angle members 51 and are locked in position by means of the nuts 52. The vertical flange 53 of each angle member 51 is secured in any suitable manner to the right hand vertical leg of each of the cradle supports 47. I have provided in the wall structure of the cabinet directly above the cooling chamber 14 two channel bars 54, 54. These bars are properly supported from the framework below the top wall and exterior of the lining as is shown in the upper part of Fig. 2. Bolts 55, 55 are secured at their upper ends to the webs of the channel bars 54, 54 and project downward through the insulating material 11 and upper lining 18 for the cooling chamber 14 and into the interior of the latter. The inwardly bent attaching members 48, 48 have slots 56, 56 formed therein for the reception of the lower end of the supporting bolts 55, 55. The supporting bolts are secured in these slots by means of spacing sleeves 57, 57 and nuts 58, 58 secured to the outer end of the bolts. The slots 56, 56 provide a means for adjusting the cooling unit 30 laterally of the cooling chamber 14. The weight of the cooling unit will tend to straighten the attaching members at the points 59, 59; but due to the natural elasticity of the metal used, this straightening tendency will be resisted, and will thereby provide a resilient supporting means for the cooling unit as will be readily understood.

It will be seen from an examination of Fig. 2 that I have provided a cover 60 closing the entire front of the cooling chamber 14. This cover will act as a guard plate to prevent the warm outside air from entering the cooling chamber 14 and also as a means for hiding the unsightly cooling unit parts during the period that the door 15 thereto is open. The exterior surface of the guard plate is covered with some suitable material such as enamel so as to present a pleasing effect to the eye and thereby serves as a finishing plate for the front of the cooling chamber. I have provided a series of openings 61, 61 in this guard plate corresponding in number to the food chambers or sleeves 43, 43 in the brine tank and adapted to align therewith. The receptacles 44, 44 for receiving food to be chilled such as desserts or the like or water to be frozen, are inserted through these openings into the food chambers or sleeves 43, 43. Plates 62, 62 are attached to the front wall of each of the food receptacles 44. These plates rest against the outside surface of the guard plate when in position, and form a closure for the openings 61, 61 in the guard plate in the manner shown. As these plates 62 abut the outer surface of the guard plate 60, they will also form in connection with the guard

plate, a means for limiting the inward movement of the receptacles. A handle 63 is provided on each plate 62 for facilitating the insertion and removal of the food receptacles as will be readily understood.

70

The outer surface of the guard plate will become frosted when the outer door 15 of the cooling compartment is closed due to the condensing and freezing on the plate of the moisture present in the air. Also, when this door is again opened the contacting air will melt some of the frost, and also an additional amount of moisture will be condensed on the plate from the air last entering. This will result in an appreciable amount of water forming on the surface of the guard plate and flowing down the front thereof and collecting on the lower horizontal portion 64. The opening 65 is provided in the lower portion 64 of the guard plate and will drain away this surplus water and thus prevent it from trickling down the outer wall or face of the refrigerator cabinet thereby injuring the finish thereof. The drainage water will pass into the chamber 14 from whence it is conducted to the sewer by means of the conduit 66.

80

85

90

95

100

105

The slots 56 in the attaching members 48, 48 provide an improved adjustable means for the brine tank supports 47, 47 thereby permitting the lateral shifting of the brine tank so that the food chambers 43, 43 therein may be placed in proper alignment with the openings 61, 61 in the guard plate. In forming the cradle supports for the brine tank with inwardly bent attaching members 48, 48 I have provided simple means for resiliently supporting the brine tank, so as to accommodate any slight vibration that may be transmitted to the cooling unit through the pipe connections between it and the compressor-condenser unit. Also, the resilient support of the cooling unit is adapted to resist shock and vibration that may be encountered during transportation.

The guard plate 60 closing the front of the cooling chamber permits access to the food receptacles and at the same time prevents warm outside air from entering the interior of the cooling chamber and raising the temperature of the air contained therein, the plates 62 making the guard plate 60 more effective to this end, and at the same time acting to limit the inward movement of the food receptacles 44. The unsightly cooling unit parts are hidden from view when the outer door is open as the guard plate closes the entire front of the cooling chamber. Also the exterior finished surface of the guard plate will present a pleasing effect to the eye. The opening 65 and the conduit 66 provide an effective means for conducting away the surplus water formed on the surface of the guard plate.

115

120

125

While I have shown and described in some detail the preferred construction and pre-

130

ferred arrangement of the parts, it will be understood that in all respects there can be wide variations without departing from the invention as defined in the appended claims.

5. What I claim as my invention is:

1. In refrigeration apparatus, the combination of a cooling chamber; a brine tank located in said cooling chamber and formed with a horizontally disposed interior food chamber opening through the front wall of the said brine tank; and a guard plate for the front of said cooling chamber formed with an opening to register with the said food chamber; said tank being adjustably supported whereby the desired alignment of the chamber with the opening in said guard plate can readily be secured.

2. In refrigeration apparatus, the combination of a cooling chamber; a brine tank located in said cooling chamber and formed with a horizontally disposed interior food chamber opening through the front wall of the said brine tank; a guard plate for the front of said cooling chamber formed with an opening to register with the said food chamber; and means for adjustably supporting the brine tank.

3. In refrigeration apparatus, the combination of a cooling chamber; a brine tank located in said cooling chamber and formed with a horizontally disposed interior food chamber opening through the front wall of the said brine tank; a guard plate for the front of said cooling chamber formed with an opening to register with the said food chamber; said tank being adjustably supported whereby the desired alignment of the chamber with the opening in said guard plate can readily be secured; a tray adapted to be inserted into the opening in said guard plate and said food chamber; and means limiting the inward movement of the said tray.

4. In refrigeration apparatus, the combination of a cooling chamber having a door opening; a cooling unit supported within the interior thereof; means for receiving a food receptacle within the said cooling unit; a guard plate closing the door opening in said chamber for excluding warm outside air, said guard plate having an opening therein for the insertion of a food receptacle into the cooling unit; and an outer door for closing said chamber opening.

5. In refrigeration apparatus, the combination of a cooling chamber having a door opening; a cooling unit supported within the interior thereof; means for receiving a food receptacle within said cooling unit; a guard plate closing the door opening in said chamber for excluding warm outside air, and having an opening therein; a food receptacle extending through the said opening and into the cooling unit; and means for limiting the inward movement of the said food receptacle.

6. In refrigeration apparatus, the combi-

nation of a cooling chamber having a door opening; a cooling unit supported within the interior thereof; means for receiving a food receptacle within said cooling unit; a guard plate for excluding warm outside air, closing the opening of the said cooling chamber, and having an opening therein; a food receptacle extending through the said opening and into the cooling unit; and means carried by the said receptacle for closing the opening in the guard plate when the said receptacle is in position within the cooling unit.

7. In a refrigeration apparatus, the combination of a cabinet comprising exterior top, bottom and side enclosing walls; attaching and bracing means for said exterior enclosing walls; a lining of insulating material located within the said enclosing walls and spaced therefrom; an inner lining for the said cabinet within the said insulating material; U-shaped channel bars supported from the cabinet structure at a point below the said top wall and exterior of said inner lining; a cooling unit located within said cabinet; and means for supporting said cooling unit from the said U-shaped channel bars.

8. In refrigeration apparatus, the combination of a cooling chamber having a door opening; an outer door for closing said cooling chamber opening; mechanically operated cooling means disposed within the interior of said cooling chamber; and a guard plate disposed between said cooling means and said outer door, and closing the opening of said cooling chamber, for excluding the warm outside air from said cooling unit.

9. In refrigeration apparatus, the combination of a cooling chamber; an outer door for closing said cooling chamber; mechanically operated cooling means disposed within the interior of said cooling chamber; a finishing plate disposed between the said outside door and said cooling means; and means for conducting away condensed moisture from the front of said finishing plate.

10. In refrigeration apparatus, the combination of a cooling chamber; an outer door for closing said cooling chamber; a cooling unit supported within the interior thereof and having means for receiving receptacles for food; and a guard plate for excluding warm outside air closing the front of the said cooling chamber when the said door is open and having an opening therein for the insertion of a food receptacle into the said cooling unit; the said guard plate having a drainage opening in the lower portion thereof.

11. In refrigeration apparatus, the combination of a cooling chamber; an outer door for closing said cooling chamber; a cooling unit disposed within said chamber and having means for receiving receptacles for food; a guard plate for excluding warm outside air from said cooling unit closing the front

of said chamber when the said door is open and having an opening therein for the insertion of food receptacles into said cooling unit; the said guard plate having a drainage 5 opening in the lower portion thereof; and means associated with the said drainage opening for conducting away condensed moisture.

12. Refrigerating apparatus comprising
10 the combination with a cabinet having a cooling compartment; of a cover for said compartment and having an opening therein; of a cooling unit adapted to be located within the compartment and having an opening
15 adapted to be arranged to register with the opening in said cover; of a support for said cooling unit, said support comprising means for adjustably securing the cooling unit in position with respect to said cover.
20 13. Refrigerating apparatus comprising the combination with a cabinet including a lining of insulating material and outer walls spaced from said lining; of a cooling unit adapted to be supported within the cabinet;
25 and means supported by the outer walls of the cabinet and located within the lining and adapted to receive the cooling unit and having provisions permitting movement of the cooling unit relative to the cabinet.
30 In testimony whereof I hereunto affix my signature.

JOHN R. REPLOGLE.
